2,256,691

KNITTED FABRIC AND METHOD

William L. Smith, Jr., Pawtucket, R. I., assignor
to Hemphill Company, Central Falls, R. I., a
corporation of Massachusetts

Application September 5, 1939, Serial No. 293,395

4 Claims. (Cl. 66—172)

This case deals with knitted fabrics in which elastic yarns have been incorporated in a manner to complete a selvage and thereafter, to render the fabric elastic generally.

In the figures of drawing:

Fig. 1 is a conventional representation of a section of fabric, loops being shown greatly enlarged;

Fig. 2 is an elevation of a half hose to which the invention may be applied; and

Fig. 3 is an elevation of a stocking top of slightly different types wherein the invention may be applied.

Referring to Fig. 1 an elastic yarn, preferably fed at an independent feeding station in a two feed knitting machine such as a hosiery machine, is taken in the hooks of every fourth needle such as would knit in wales 2, 3, 4 and 5. It is to be understood that at this time the feeding of this elastic is merely for the purpose of loading it within hooks of needles and there is no provision for clearing latches nor casting loops from these needles until a later time. At the main side of the machine at which it is preferred to feed a non-elastic yarn or yarns no knitting is being done so that in effect, that part of the machine is relatively inactive. Then for three revolutions more or less, said elastic yarn is taken in the hooks of every intermediate fourth needle, that is, those needles knitting in wales 6, 7, 8, etc. At this time four courses have been loaded, one in the hooks of the first mentioned needles and three in the hooks of those second mentioned. It is to be understood that the elastic is fed under slight tension. When released it will contract and straighten out, then appearing as several stretches of elastic threaded through sinker loops or a following course.

The elastic yarn is then fed to every second needle and is drawn into knitted loops in course A, casting off the previously held elastic. Thereafter two courses of non-elastic yarn 9 are fed and knitted at the so-called main side of the machine, these resulting in the courses B and C. This completes a selvage and gives the course C as a sort of anti-curl or anti-roll barrier before elastic is again introduced to be incorporated in some desired manner throughout the remainder of the stocking top thereby to produce a garter. From this point it is preferred to knit the elastic and inelastic yarns as in St. Pierre Patent #2,131,720. In that way the elastic is incorporated under a slight tension by knitting independently on every other needle at the auxiliary

side and by knitting the non-elastic yarn at every needle at the main side.

While that type of fabric is preferably knitted in continuation of the selvage and intervening course or courses such as C, other types of garter top may be knitted in which the elastic will be knitted, inlaid, or otherwise incorporated at spaced wales so as to draw those wales together to simulate a rib appearance and to constitute the stocking top as a garter.

In Fig. 2 a half hose is shown to which the invention may be applied, the top 10 being knitted in a manner described above, the selvage 11 being formed by the loaded elastic, course A and non-elastic yarn course B. The course or courses such as C would be evident at 12 and it is to be understood that elastic is to be withdrawn for a period of time sufficient to knit a desired amount of this non-elastic fabric intervening between the edge and the remaining part of the garter top as may be found most satisfactory to prevent rolling of the fabric.

Referring to Fig. 3, the invention may be applied to a fabric in which that portion of the top indicated at 13 is knitted as illustrated in Fig. 1 while a part of the top at 14 is to be knitted similarly except that the elastic is to be drawn into independent stitches at more widely spaced wales than every other wale. For example, the elastic might be knitted on every fourth needle or every sixth needle. The non-elastic zone as at 12 may also intervene between an edge 15 and the zone 14. The invention is defined in the appended claims.

I claim:

1. A knitted stocking top having a selvage including an elastic course drawn into knitted stitches at every second wale and having incorporated therein several stretches of elastic, these being held by being threaded through sinker wales of said course of elastic, some through sinker wales adjacent spaced stitches and others through sinker wales adjacent stitches intermediate those spaced stitches.

2. A knitted fabric having a selvage including elastic, several stretches of which have been loaded in predetermined wales and a final course drawn into knitted loops at every second wale, a plurality of non-elastic yarn courses following said final course of elastic, thereafter a plurality of courses in which elastic and non-elastic yarns are knitted to form a garter top.

3. A method of knitting including the steps of knitting a selvage having a course of elastic yarn and several stretches of elastic threaded through

sinker loops of that elastic yarn course, then knitting a plurality of courses of non-elastic material without elastic incorporated therein, and thereafter knitting non-elastic and elastic yarns so that the elastic will be incorporated under slight tension and at spaced wales.

4. A method of knitting as in claim 3 wherein

the non-elastic and elastic material knitted simultaneously are first knitted through a zone in which the elastic is incorporated at wales relatively widely spaced and then throughout a continuing portion of the stocking top at more closely spaced wales.

WILLIAM L. SMITH, JR.
